UNITED STATES PATENT OFFICE.

ALICE ANTHONY, OF STERLING, ILLINOIS.

DARNING LAST.

Application filed July 3, 1924. Serial No. 723,863.

My invention relates to lasts or mending forms adapted to facilitate the darning of hosiery, and has for its object the provision of a device of such class which shall be of greater usefulness and adaptability for service than any hitherto known. The darning forms heretofore most largely used are all, so far as I am aware, of a relatively thick and distinctly rounded or bulbous form, in some cases slightly flattened, but in general approximately more or less closely a globular shape. The curvature of the surface of these darning forms is therefore of such short radius that a darning 5 needle cannot readily be woven in and out in making a darn across a rent of any considerable size, and the short, thick, rounded shape of such a form renders it difficult to handle and hold in place, unless it is provided with a handle, which renders it less manageable and less easily adjustable in the 10 sock. Moreover, unless of unusual and inconvenient size, an approximately globular darning last will readily pass through a rent of large size, and it is therefore impracticable as an aid in making a repair of such a hole. In some cases forms having both a leg portion and a foot portion have been proposed, but such forms are altogether 15 inconvenient and unwieldy for practical use and great care must be exercised in slipping a stocking over such a form to avoid enlarging the holes because of the bend at the ankle, in addition to which adjustment of 20 the stocking to different positions on the form cannot be made.

With the purpose in view of providing a device which shall overcome the objections mentioned, I have designed and invented the novel darning last hereinafter described in detail, the essential elements of my invention being more particularly pointed out in the appended claims.

In the accompanying drawings forming part of this specification, Figure 1 is a full size edge view of a single size 9 last; Fig. 2 is an end view of the same; Fig. 3 is a side view on a smaller scale of a sock in which a last (indicated in dotted lines) has

been inserted, the last being arranged with 50 the uppermost longitudinal edge disposed along the center line of the sole portion of the sock; Fig. 4 is a similar view, but with the last arranged with one side face against the sole of the sock; Fig. 5 is a view showing the sole of the sock stretched over the side face of a last; and Figs. 6 and 7 are views of a long stocking with an inserted last in the leg portion of the stocking for repairing a hole at the knee, and for darning a "runner", respectively.

The same reference characters indicate the same parts in all the figures of the drawing.

My improved darning last is preferably 65 formed of a hard or semi-hard wood, such as birch, with the grain running lengthwise of the device, and is best polished to a smooth finish. Any hard light material or composition, however, as hard rubber, celluloid, aluminum, hollow enameled ware, glass, etc. may be used. I contemplate supplying my darning forms in complete sets of lasts of different sizes, numbered to indicate corresponding stocking sizes. How- 70 ever, a single last may be supplied, correspond- 75 ing to the size of hosiery worn by the purchaser, or a set consisting of a limited number of selected sizes, as, by way of a typical example, one men's size last between 80 Nos. 9½ and 11, one ladies' size, between 8 and 10, one children's size, between 6 and 9, and one infants' size between 4 and 6. Whatever their sizes the lasts are relatively 85 broad and thin, approximately the shape of the sole of a sock of corresponding size, with rounded ends. In Figs. 1 and 2 I have shown in full size a No. 9 last having the dimensions which I have found most suitable for the purpose, although the propor- 90 tions may be varied somewhat and the dimensions there indicated are stated only by way of exemplification of the form which I regard as most desirable. As there illus- 95 trated, the thickness of the last along the center portion of its body is slightly less than one-fourth of its width and slightly more than one-tenth its length. The last

therefore has opposite side faces which are tickle to restore the entire toe or the entire heel of a sock and form it of the same size and shape as the article originally possessed. With a darning form of spherical, or egg-shaped, or somewhat flattened bulbous form,⁷⁰ such manipulation is impossible, and the sock is almost inevitably stretched to a considerable and undesirable degree adjacent the margin only of the rent. The interlaced cross stitches which constitute the darn,⁷⁵ moreover, must be laid over a convex surface having considerable curvature, and the darn is therefore more or less cupped, and does not lie as smooth and present as neat an appearance as a repair made on the relatively⁸⁰ slightly curved face of my novel darning last.
10 of the side surfaces being carried around the end portions of the last, as indicated in Fig. 1. In longitudinal section, as will be obvious from Figure 1, the intermediate portions of opposite side faces are not
15 curved, or convexed to the same degree as the ends of said faces to provide for substantially flat surfaces, as viewed in longitudinal section. The longitudinal and transverse cross sections of the last may perhaps be more accurately defined as being substantially elliptic-lanceolate because of the thin peripheral edge of the last. While the last is perhaps not strictly geometrically elliptical in longitudinal section, it is substantially so, and I desire it understood that my claims defining the cross sectional shape of the last are to be construed as covering a true geometrical elliptical cross section, an elliptic-lanceolate cross section as well as
30 all variations thereof which fall within the scope of my claims.

As before indicated, the broader end of the last may be termed the "toe" end, and the narrower the "heel" end of the last.
35 Conforming, as it does, to the shape of the stocking foot, a last of appropriate size will therefore fit the stocking with a uniform stretch of the material when inserted therein. The last may be arranged within the stocking either as shown in Fig. 3 or in Fig.
40 4, or at any intermediate position which will bring a rent into the most convenient position to make a repair. Ordinarily, this position will be one in which the hole to be darned will lie on the face of the last and conveniently near its edge, as shown at *a* and *b* in Fig. 3; *c*, *d* and *e* in Fig. 5. Preferably the larger holes are darned first, and the stocking adjusted on the last as necessary.
45 Preferably, also, the large end is used in darning large holes as this affords more space wherein to weave the thread and avoids tight weave of the work when finished, and thus provides for laundry shrinkage.
50 With a last of appropriate size, all the holes are displayed and the foot of the stocking is slightly but uniformly stretched throughout its entire extent over a nearly flat surface, curved just enough to enable a needle to be employed most advantageously.
55 All of the thin places will be readily discovered and continuous darning over a group of many small holes, such as often appear in fine hosiery will be facilitated. With my novel form of last, it has been found prac-

My last is also peculiarly desirable for darning what are known as "runners," which often appear in the leg portions of long⁸⁵ stockings. These are due to the breaking of a thread which permits a longitudinal line of stitches of the knitting to become disengaged and display a conspicuous line of small openings. The extended, slightly rounded side face of my darning last is admirably adapted to facilitate a repair of such a defect, when the last is arranged within the stocking leg as shown in Figs. 6 and 7 and the opposite ends of the stocking⁹⁵ are held tightly together on the under side of the last along with the underlying portion of the stocking, thus providing an equal and uniform stretch on top. If desired the ends of the stocking may be tied in a loose knot, or for men's socks a safety pin may be applied to secure the ends together underneath the last.

The last may be placed in the stocking with either the larger end—the toe of the last—in the toe of the stocking, or the smaller end, as may best suit different sizes of stockings, various positions of rips to be mended, etc., or it may be arranged at any angle within the stocking which may suit the convenience of the worker. In applying the last it will be found convenient to hold it flat and placed against the body, using both hands to slip the stocking on. With the last within the stocking lengthwise the stocking¹⁰⁵ may be slipped sideways or lengthwise to adjust the holes to its face, and the last removed only to change its position end for end. The difference in size of the ends of the last presents the advantage that a single last may be used to repair hosiery of different sizes, or to provide a variation in the degree of stretch of the fabric on the last. The shape of the last is such that it may be held and used in many and varied positions, which renders its use less tiresome than that of any darning last heretofore known.
110

I claim:

1. A substantially stiff darning last of substantially oval outline, said last being sub-¹³⁰

stantially elliptical in transverse cross section and being of appropriate size to fill a corresponding stocking foot.

2. A substantially stiff darning last of 5 elongated substantially oval outline, said last being substantially elliptical in transverse and longitudinal sections, and being of appropriate size to fill a corresponding stocking foot.

3. A relatively flat rigid darning last of 10 elongated substantially oval outline having opposite slightly curved faces tapering towards a thin rounded edge at its periphery, and being of appropriate size to fill a corresponding stocking foot.

ALICE ANTHONY.
